UNITED STATES PATENT OFFICE.

OLIVER H. YOUNG, OF BROOKLYN, NEW YORK.

ANTISKIDDING DEVICE FOR VEHICLES.

1,141,676.

Specification of Letters Patent.

Patented June 1, 1915.

Application filed May 23, 1914. Serial No. 840,409.

To all whom it may concern:

Be it known that I, OLIVER H. YOUNG, a citizen of the United States, residing at 239 Steuben street, Brooklyn, New York, have 5 invented new and useful Improvements in Antiskidding Devices for Vehicles, of which the following is a specification.

This invention relates to an improvement in antiskidding devices for vehicles and 10 more especially for automobiles.

One of the objects of the invention is to provide a device of this character which may be attached to any type of wheel without necessitating any alteration in the con- 15 struction thereof.

Another object is to provide a device of this character which may quickly and easily be placed in or out of operative position.

Other objects are to provide a device of 20 this character which will be efficient in operation, simple in construction, not liable to get out of order, and inexpensive to manufacture.

Other objects will in part be obvious and 25 in part be pointed out hereinafter.

In the accompanying drawings illustrating several embodiments of the invention and in which the same reference characters refer to similar parts throughout the several figures, Figure 1 is a side elevational view of one embodiment of the invention, parts being broken away for the sake of clearness; Fig. 2 is a vertical sectional view of Fig. 1; Fig. 3 is a view similar to Fig. 1 showing a slightly modified form; Fig. 4 is a vertical sectional view showing a modification of the invention; Fig. 5 is a side elevational view of Fig. 4; Fig. 6 is a view similar to Fig. 1 showing another modification; 40 Fig. 7 is a vertical sectional view showing a further modification of the invention.

Referring to the drawings, 1 indicates the spokes and 2 the felly of a wheel of any suitable construction provided with a tire 3. 45 It will of course be understood that the invention may be used in connection with any form of wheel and any type of tire without in any way departing from the spirit of the invention.

50 Referring to Figs. 1 and 2 of the drawing, 4 indicates brackets of any suitable construction which are adapted to be secured to the

wheel in any suitable manner, and which support an annular member 5 provided with outwardly extending flanges 6, 6. Bars 7 55 are reciprocatingly carried by the annular member 5 and have their outer ends secured in any suitable manner to resilient members 8 which have a double looped or S shaped formation. As shown in Fig. 1 the members 8 are united to one another by substantially straight portions 8'. The resilient members are preferably formed of tempered steel or the like in order to provide the required elasticity and strength. To the 65 lower portion of the looped shaped members 8 are secured ground engaging members 9 which are preferably provided with a concave lower surface.

Rotatably supported in grooves 10 of the 70 flanges 6 is a ring 11 provided with inclined slots 12 adapted to receive pins 13 carried by the supporting rods 7, as clearly illustrated in Figs. 1 and 2. It will be understood that as the ring 11 is turned each of 75 the pins 13 will be caused to travel up or down its cooperating inclined slots 12 thereby raising or lowering the supporting rod 7 associated therewith.

As shown in Figs. 1 and 2 the ground en- 80 gaging members 9 are in their lower or operative position, and they would be raised to occupy their inoperative position by turning the ring 11 in a clockwise direction, which movement of the ring will cause the 85 pins 13 to ride up the inclined slots 12 and into engagement with the upper ends thereof. As shown in these figures the ring 11 is provided, for a portion of its inner circumference, with teeth 14 which are engaged by 90 a toothed wheel 15 mounted upon one end of a shaft 16 rotatably supported upon the wheel in any suitable manner, and having its opposite end 17 squared to be engaged by a wrench or other suitable tool whereby 95 the shaft 16 may be turned. It will thus be understood that when it is desired to raise or lower the ground engaging members 9 it is merely necessary to apply a suitable tool to the squared end 17 of the shaft 16 and to 100 rotate the shaft in the desired direction.

Referring to Fig. 3 the device is substantially the same as that shown in Fig. 1 with the exception that the resilient members 8

are not connected to one another. While in these figures a supporting rod 7 is shown adjacent each spoke of the wheel it will of course be understood that the number of supporting rods and their positions may be varied as desired without in any way departing from the spirit of the invention.

Referring to Figs. 4 and 5, there is shown an electrically controlled means for turning the ring 11 which reciprocates the supporting rods 7. 19 indicates an electro-magnet mounted upon the flanges 6 of the annular member 5, and having its armature 20 connected to the ring 11. This magnet is connected by wires 21 and 22 to contact rings 23 and 24 carried by the drum 25 which rotates with the wheel. Bearing upon the rings 23 and 24 are contacts 26 and 27 which are electrically connected with a two way switch 28 and a source of electrical energy such as a battery 29. A second magnet, (not shown) oppositely disposed with respect to the ring 11, is mounted upon the member 5 at another point thereof. It will be understood that by throwing the switch 28 into one or the other of its operative positions one or the other of the magnets will be energized to attract its armature 20, thereby turning the ring 11 and causing the ground engaging members 9 to be raised or lowered.

In order to adjust the parts to conform to the tire and to hold the rods 7 in such adjusted position, the inner flange 6 of the annular member 5 is provided with locking devices 38 and 39, as shown in Fig. 6. Each of these locking devices comprise a locking member 40 mounted in a recess 41 and normally held in locking position by means of a spring 42. The locking member 38, which locks the rods in their raised position, is preferably fixed with respect to the flange 6, while the other locking member 39 is adjustably mounted on the flange, being provided with a slot 43 adapted to receive a headed screw 44 which engages the flange 6. By loosening the screw 44 the locking member 39 may be moved relatively to the flange, for the purposes herein-after set forth. The ring 45, which corresponds to the ring 11 shown in Fig. 1 and which serves the same purpose, is provided with a projection 46 having a notch 47 formed therein, which notch is adapted to receive one or the other of the locking members 40, as clearly indicated in the drawing. The parts are so arranged and proportioned that when the notch 47 receives the locking member 40 in the fixed locking device 38 the rods 7 will be in their uppermost position and the ground engaging members in their inoperative positions. When the notch 47 is in engagement with the locking member 40 in the movable locking device 39 the ground engaging members

will be in their operative position. It will therefore be understood that the position of the ground engaging members relatively to the wheel may be adjusted to conform with the tire which is carried by the wheel, and it will also be understood that the ground engaging members will be locked against movement in their adjusted positions. If, for example, it is found that the ground engaging members do not engage the ground with sufficient force to prevent skidding it is merely necessary to move the member 39 to the right (as seen in Fig. 6) a sufficient distance and then to move the ring 45 in an anti-clockwise direction until the notch 47 engages the locking member 40 in the locking device 39.

In Fig. 6 the resilient members 8 are shown as being provided with a substantially straight portion 49 adapted to be secured to the adjacent supporting rod 7, although it will of course be understood that the forms shown in the other figures could be employed therefor if desired.

Referring to Fig. 7 there is shown a mechanical means for turning the ring 11 which means can be controlled by the driver of the vehicle from the driver's seat. This means comprises crown gears 50 and 51 frictionally mounted in grooves in the drum 25 and normally rotating therewith. The gear 50 meshes with a gear wheel 52 mounted on a shaft 53 extending radially of the wheel, and the gear 51 meshes with an idler 54 which in turn meshes with a gear wheel 55 also mounted on the shaft 53. Secured to the outer end of shaft 53 is a gear wheel 56 meshing with teeth on a flange 57 carried by the ring 11. Rods 58 and 59 are provided with threaded portions engaging a stationary part of the frame 60, and these rods are adapted to be rotated by suitable levers, not shown, under the control of the driver. These rods are normally maintained out of engagement with the crown gears 50 and 51, but by rotating either of the rods in the proper direction it will be moved into engagement with its corresponding crown gear and the pressure exerted by the rod upon the gear will prevent the latter from rotating with the drum 25. As a consequence of one of the crown gears being held stationary the gear wheel associated therewith will be forced to rotate about its axis as the wheel rotates, thereby causing the ring 11 to turn. It will of course be understood that by reason of the idler gear 54 the shaft 53 may be rotated in opposite directions depending upon which of the crown gears 50 or 51 is held stationary with respect to the drum.

The operation of the device, which should be largely obvious from the above description, is as follows: When the roads upon

which the vehicle travels are in a condition such that there is no liability of skidding, the ground engaging members are held in their raised or inoperative positions. If, 5 however, the roads are slippery and there is danger of skidding the ground engaging members are moved into their lower or operative positions, in which positions they will engage the road bed and, by reason of the 10 pressure which they exert thereon, lateral or skidding movement of the vehicle is prevented. Owing to the fact that the ground engaging members are resiliently mounted the device will in no way interfere with the 15 resiliency of the tires and the smoothness with which the vehicle travels will not be affected. By recessing the surface of the ground engaging members their effectiveness is increased as the sharp edges formed 20 by the recess will easily pass through any mud, ice or the like and into engagement with the road surface.

Having described this invention in connection with the illustrative embodiments 25 thereof, to the details of which disclosure the invention is not, of course, to be limited, what I claim as new, and what is desired to be secured by Letters Patent is set forth in the appended claims:

30 1. In an anti-skidding device, the combination with a wheel, of a plurality of circumferentially spaced radially reciprocable members mounted upon the wheel, a radially compressible spring associated with each of 35 said members and having one of its ends secured thereto and disposed inwardly with respect to its opposite end, a ground-engaging member carried by the outer end of each spring, and common means associated with 40 all of the reciprocable members by which they may be adjusted simultaneously and secured in adjusted position.

2. In an anti-skidding device, the combination with a wheel, of a plurality of circumferentially spaced radially reciprocable members mounted upon the wheel, a radially compressible spring associated with each of 45 said members and having one of its ends secured thereto and disposed inwardly with respect to its opposite end, an elongated circumferentially inclined spring extension connecting the outer end of each spring with the inner end of an adjacent spring, a ground-engaging member carried by the 50 outer end of each spring, and means by which the said reciprocable members may be adjusted and secured in adjusted position.

3. In an anti-skidding device, the combination with a wheel, of a plurality of circumferentially spaced radially reciprocable members mounted upon the wheel, a radially compressible spring associated with each of 55 said members, and having one of its ends secured thereto and disposed inwardly with

respect to its opposite end, a ground-engaging member carried by the outer end of each spring, and means by which the said reciprocable members may be adjusted simultaneously and secured in adjusted position.

4. In an anti-skidding device, the combination with a wheel, of a plurality of circumferentially spaced radially reciprocable members mounted upon the wheel, a radially compressible spring associated with each of 65 said members and having one of its ends secured thereto and disposed inwardly with respect to its opposite end, an elongated circumferentially inclined spring extension connecting the outer end of each spring with the inner end of an adjacent spring, a 70 ground-engaging member carried by the outer end of each spring, and means by which the said reciprocable members may be adjusted simultaneously and secured in adjusted position.

5. In an anti-skidding device, the combination with a wheel, of a plurality of circumferentially spaced radially reciprocable members mounted upon the wheel, a ground-engaging member carried by each of said reciprocable members, an annular member mounted upon the wheel for circumferential adjustment and provided with a plurality of diagonal slots corresponding in position to the said reciprocable members, a lateral 75 pin projecting from each of the last-named members for engagement within the corresponding slot of the annular member, and means by which the annular member may be adjusted, the said slots of the annular member having their end portions extended circumferentially.

6. In an anti-skidding device, the combination with a wheel and an axle rotatably mounting the wheel, of a plurality of circumferentially spaced radially reciprocable members mounted upon the wheel, a ground-engaging member carried by each of said reciprocable members, an annular member mounted upon the wheel for circumferential 80 adjustment, means connecting said annular member with each reciprocable member whereby the latter will be reciprocated upon adjustment of the former, stationary operating means mounted upon the said axle, and means carried by the wheel and associated with the said operating means for causing adjustment of the annular member upon actuation of the operating means.

7. In an anti-skidding device, the combination with a wheel, of a plurality of circumferentially spaced radially reciprocable members mounted upon the wheel, a substantially S-shaped spring associated with each of said members and having one of its 85 ends secured thereto and disposed inwardly with respect to its opposite end, an elongated spring extension connecting the outer end of

each spring with the inner end of an adjacent spring, a ground-engaging member carried by the outer end of each spring, and means by which the said reciprocable members may be adjusted and secured in adjusted position.

In testimony whereof I have signed my

name to this specification in the presence of two subscribing witnesses.
